THERMOSTATIC CONTROL FOR ELECTRIC CIRCUITS

Filed Dec. 30, 1930

UNITED STATES PATENT OFFICE

1,959,659

THERMOSTATIC CONTROL FOR ELECTRIC CIRCUITS

Gus L. Colbie, Brooklyn, N. Y., assignor to Hudson Electric Heating Corporation, New York, N. Y., a corporation of New York

Application December 30, 1930, Serial No. 505,537

4 Claims. (Cl. 200—139)

My invention relates to an improved method of thermostatic control for electric circuits, and comprises (in the form here illustrated) certain improvements on the type of thermostatic apparatus shown in U. S. Patent No. 1,762,174, to Emil F. Holinger, dated June 10th, 1930.

One object of my invention is to simplify the structure and provide a more positive action to the operating parts.

Another object is to provide a curved or arcuate bi-metallic element which responds quickly to temperature changes and permits the placement of operating members within a confined area thereby providing a thermostatic unit which is adaptable for many uses.

Another object is to provide an internal adjustment for the bi-metallic member for certain broad predetermined temperature ranges and an external adjustment for varying the original adjustment and control the temperature within said broad range.

Another object is to provide a circuit breaker which breaks the electrical contact across two terminals.

These and other features are set forth in the following specification and drawing, wherein:

Figure 1 is a front view of my device with the cover of the casing removed;

Fig. 2 is a vertical central section taken on the line 2—2 of Fig. 1, showing the casing attached to the wall of a room;

Fig. 3 is a rear view of the casing;

Fig. 4 is a front view of a portion of the casing and cover showing the external adjusting lever; and

Fig. 5 is a view similar to Fig. 1 of the operating parts, showing said parts in operating position with the ratchet actuating pawl and contact terminal wipers in a position just prior to engagement with the next following teeth of ratchet and circuit breaker wheel.

Briefly, my improved device comprises a ratchet wheel having a rotary circuit breaker attached thereto, said ratchet wheel being engaged by oppositely disposed pawls which are secured to the free moving end of a substantially inverted U-shaped bi-metallic element. At certain predetermined temperatures, the free end of the bi-metallic element is moved outward or inward when heated or cooled, and one of the ratchet operating pawls rotates said ratchet wheel through a distance of one-half a tooth, the opposite pawl sliding over a whole tooth due to the movement of the ratchet wheel and the latter pawl in opposite direction. The cir-

cuit breaker has in engagement with its periphery a pair of metallic wipers each of which is connected with an electrical line leading to certain electrical devices to be controlled such as the motor on an oil burner, a blower for a house heating furnace, or for oven-heat control. The periphery of the circuit breaker is arranged with alternate metal and insulating contacting surfaces and the wipers are adapted to engage either two metal surfaces or two insulating surfaces during each partial rotation of the ratchet wheel a distance of one-half a tooth. When the bi-metallic member is expanded by heat, and the ratchet wheel is rotated through one-half a tooth, the circuit breaker attached thereto would move through a distance of one tooth to break the electrical circuit and on cooling, the bi-metallic element approaching its normal position would cause the ratchet wheel to rotate through the distance of another half tooth, by the action of the opposite pawl, while the circuit breaker rotates through a distance of one full tooth to permit the contact wipers to engage the metal surfaces and complete the electrical circuit.

In Fig. 1, I have shown a housing 10, in which is contained the thermostatic control apparatus designated generally by the reference character 12.

A horizontally disposed shaft 14 having an enlarged outer end 16 is riveted at its inner end to the back wall of the casing 10 at 18, and has mounted thereon a ratchet wheel 20. The ratchet wheel 20 comprises ratchet teeth 22, a shoulder 24, and a reduced hub 26, the whole being confined between the edge of a shoulder 15, on the shaft 14, and the inside surface of the back wall of the casing 10.

A rotary circuit breaker 28, comprising a metallic disc 30 imbedded in an insulating disc 32, is passed over the hub 26 of the ratchet wheel 20 and secured to the shoulder 24 of said ratchet wheel by means of pins 34. The periphery of the circuit breaker has equally spaced tooth shaped portions 36, the spacing of which is designed to have two teeth on the circuit breaker equal to one on the ratchet wheel, as indicated by the broken radial lines A—A. The tooth shaped portions 36 are adapted to be engaged by a pair of tensioned electrical contact wipers 38 and are arranged so that said wipers 38 will engage either two metal surfaces 40 or two insulating surfaces 42 at the same time. To prevent sparking or any reverse rotation of the ratchet, a beveled edge 44 is provided on each of the insulating teeth 42 at the

60

75

80

85

90

95

100

105

110

point where the wipers 38 snap off the edge of each metallic tooth.

An insulating support member 46 is secured to the rear wall of the casing 10 and has mounted thereon the two contact wipers 38, each of which has fastening ears 48 formed at right angles to the wiper blades 38 and has openings 50 through which bolts 52 are inserted. Nuts 53 fit over the threaded ends of bolts 52, engaging the ears 48; and two lead-in electrical contact wires 54 are secured to the ears 48 in any convenient way.

A bi-metallic thermostatic element 56 having a substantially inverted U-shape is mounted within the casing 10. One end 58 having an opening 60 is slipped over an inwardly disposed stud 62, said stud being mounted in a bearing 64 formed integrally with the casing 10. The end 58 is held in a fixed position by means of a coil spring 66 positioned around the inside projection of the bearing 64 and engaging the outer surface of the end 58, and a nut 68 which is screwed on the threaded end 70 of the stud 62 engaging the inner surface of said end 58. A cotter pin 67 engages slots 69 in the nut and a slot 71 in the stud 62.

The opposite end 72 of the bi-metallic element 56 is free to move along an inwardly disposed guide pin 74 secured to the casing 10, said pin engaging an opening 76 in the end 72. A spring metal strip 78 is formed with two inwardly disposed arms 80, 81, and is secured to the end 72 of said bi-metallic element 56. The ends of the arms 80, 81 are formed into pawls 82, 83, which are adapted to engage the teeth 22 of the ratchet wheel 20. The upper pawl 82 is bent so that its lower surface engages the surface of a tooth along the upper portion of said ratchet wheel, while the lower pawl 83 is adapted to engage a tooth on the opposite or lower portion. The lower arm 81 has a slot 84 cut through it to provide clearance for the teeth 22.

Certain specific settings of mean temperature may be made which will vary according to the use of the said thermostat; for instance, if the thermostat is to be used for room temperature the mean temperature would probably be 70 degrees, or if used in oven heat control the average mean temperature would approximate say 300 degrees. An initial factory setting is made to fix the position of the bi-metallic member for either a mean room temperature, or a mean oven temperature, and additional means is provided to make external adjustments to determine a working range of operation.

To make the initial factory setting, the end 58 of the bi-metallic element is adjusted (at room temperature if the thermostat is to be used in a house heating system) along the stud 62 by the nut 68 so that the edges 86 and 87 of the pawls 82 and 83 are in engagement with the working face of the ratchet teeth 22, and any movement on the part of the free end of said bi-metallic element will cause the ratchet wheel to rotate.

When the thermostat is to be used to control room temperature, the range would probably be between 65 and 75 degrees, whereas the temperature range for oven heat control would be between 200 and 500 degrees. The initial factory setting of the bi-metallic element would differ according as it is to be used for controlling room or oven temperature. The positions shown in the drawing would be correct for room temperature control, but for oven control the inner face 75 of the pawl strip 78 secured to the free end 72 of the bi-metallic element would engage the shoulder 77 on the pin 74 with enough tension to allow

the temperature to rise to about 150 degrees before the said free end moves outward. If desired, bimetallic elements of different dimensions may be provided at the factory for each condition instead of varying the position of one element.

The external means for adjusting the initial setting consists of a lever 88 fixed to the stud 62, mounted outside of the casing 10 on the outer extension of the bearing 64, which is adapted to be rotated through an angle of about 90° and provide a longitudinal movement to the stud 62 and the end 58 of the bi-metallic element in an outward or inward direction. The lever 88 comprises a flat portion 87' having an inwardly disposed upper portion 90, the corners 92 and 93 of which are adapted to contact with the cover 94 to limit the movement of said lever about its pivot 95. At the lower end of said lever 88 is an inwardly disposed lug 97 which is adapted to engage the periphery of the casing 10, and when the lever is moved, the curvature of said periphery provides a cam surface which causes the lever 88 and the stud 62 to be moved outward or inward. Since the end 58 of the bi-metallic element is secured to the stud 62 it moves a distance equal to the movement of said stud and is retained in any intermediate position by means of the pressure of the spring 66 against the outer face of the bi-metallic end 58.

This device is particularly adapted for use in rooms for controlling the temperature in same, and therefore the casing 10 is provided with stamped feet 96 which are offset to hold the casing in spaced relation to the wall for air circulation, the air passing through the openings 98 left after stamping and through additional openings 99. Holes 100 are provided to accommodate screws 102 when the casing 10 is secured to a wall.

The operation is as follows:

The position of the parts as shown in Fig. 1, with the contact wipers in engagement with the metal contact surfaces 40, indicate that the room temperature is low and a circuit has been completed to the heating device to supply additional heat. As the heat increases, the free end of the bi-metallic element expands or moves outward carrying with it the pawls 80-81. The lower pawl 81 engages the working face of one ratchet tooth 22 causing the ratchet wheel and circuit breaker to rotate slightly. When the parts are in the position shown in Fig. 5, the desired temperature has about been reached, and the contact wipers are about to snap off the surface of the contact teeth to the surface of the insulating teeth to break the circuit of the heat supplying means. As the room is cooled, the free end 72 of the bi-metallic member returns to normal position and the ratchet wheel is rotated by the upper pawl 80 until the contact wipers are brought into engagement with another set of contact surfaces to complete the circuit again. These operations are automatically repeated as the temperature changes.

Among the advantages of the invention may be mentioned the compact arrangement resulting from the nesting of all the circuit breaking mechanism within the semi-circular, temperature responsive strip, the locating of the secondary temperature adjusting element outside of the casing, the production of a double break in the controlled circuit and the ventilating back for the thermostat casing produced by stamping out the feet 96, 96' from the back thereof.

Various changes could be made in the details

of construction herein shown and described without departing from the essence of my invention so long as the above features of construction or operation, or some of them, are preserved.

5 Having described my invention, I claim:

1. In a thermostat the combination of a circuit breaking and making mechanism with a substantially semi-circular temperature responsive element having one free end adapted to actuate the circuit breaking mechanism, and one

80

10 circuit breaking mechanism, and one end mounted upon a longitudinally movable stud, means for adjusting said latter end along said stud for one adjustment and means for adjusting the stud for another adjustment.

85

15 2. In a thermostat having an element adapted to be varied in form by changes in its temperature, circuit breaking means operatively connected to one portion of said element and a cylindrical casing for the above described mechanism,

90

20 an anchorage member projecting through the casing wall to which another portion of said temperature responsive element is connected, which anchorage member comprises a stud extending through a tubular bearing in said casing

95

25 wall, together with a spring bearing in said casing wall, and tending to draw said stud into said casing, and a cam member mounted on the outwardly projecting end of said stud and bearing on the curved exterior of said casing, whereby,

100

30 on swinging said cam member on said stud as an axis, the spring is flexed and the stud and attached portion of said temperature responsive element moved radially of the casing.

3. In a thermostat, a circuit breaking and making mechanism and a casing enclosing same, in combination with a semi-circular temperature responsive element having one free end adapted to actuate the circuit breaking mechanism, and one end anchored on a stud freely mounted in a bearing on the casing wall extending inwardly thereof, an adjusting nut on said stud forming a stop for the anchored end of the temperature responsive element, a spring engaging the opposite surface of said temperature responsive element and a lever secured to a portion of said stud extending outside of said casing wall, whereby adjustments of the anchored end of the temperature responsive member can be made both inside and outside of said casing to vary the temperature ranges.

4. In a thermostat for controlling electrical circuits, the combination with a temperature responsive element mounted within a cylindrical

95

95 casing, of an anchorage for one end of said temperature responsive element, means to adjust said end along said anchorage, a lever joined to the external end of said anchorage, having a portion thereof in engagement with the exterior of the 100 casing wall and adapted when moved, to be cammed outward by its movement over said wall, whereby the said anchorage is given an external adjustment.
